UNITED STATES PATENT OFFICE.

EDWIN N. CHANDLER, OF BRAINTREE, MASSACHUSETTS.

ELECTRICALLY-HEATED SHOE-TREEING IRON.

1,348,263.

Specification of Letters Patent.

Patented Aug. 3, 1920.

Application filed November 23, 1915. Serial No. 62,968.

To all whom it may concern:

Be it known that I, EDWIN N. CHANDLER, a citizen of the United States, and resident of Braintree, county of Norfolk, and State 5 of Massachusetts, have invented an Improvement in Electrically-Heated Shoe-Treeing Irons, of which the following description, in connection with the accompanying drawings, is a specification, like letters 10 on the drawings representing like parts.

My present invention is an improved electrically heated hand tool, particularly useful as a shoe treeing, burnishing, and finishing tool.

In the manufacture of shoes it is necessary to subject the shoe to the treeing or ironing operation and the electrically heated hand treeing machines heretofore employed have been objectionable in actual practice. Such 15 prior devices were heavy, somewhat cumbersome, and usually supplied the electrical heat through the handles. This method of heat supply, besides the weight and size of the treeing iron to receive the electrical heating 20 appliance, caused undue fatigue and exertion on the part of the operator, the handles partaking very considerably of the heat and quickly dissipated the operator's strength, in addition to the weight and cum- 25 bersomeness of the treeing tool. As such a hand operated treeing tool must necessarily be entirely free from interference with the heat supply wires, it was presumed necessary 30 to lead such wires through the handles to keep same out of the way. However, according to my present invention, I am enabled to have either or both handles on the treeing iron completely and perfectly insulated from the heat of the treeing tool, and 35 also to have such treeing tool made of extremely light weight, including means to concentrate the heat on the desired surfaces and edges. I also utilize a construction 40 which will enable the handle or handles to be kept cool by air circulation and which 45 eliminates the necessity of leading the heat supply wires through any handle. In my improved electrically heated hand tool I 50 contemplate the utilization of a removable unit heater or cartridge, and preferably I construct my treeing iron to be made with the electrical heater carrier leading out of the way of the work and of the handle, both 55 handle and heater being separately removable and also conducting the heat supply wires in a manner free from annoyance or

interference with the operator or the treeing operation. This is of vital importance, as in treeing a shoe with a hand iron of this type it is necessary to manipulate the iron 60 about the shoe in a way which requires absolute freedom of movement. By conducting the heat supply wires in a manner other than through the handles I am enabled to form said handles free and open with air 65 circulating means entirely therethrough, thus insuring that the handles will remain cool under all conditions, while permitting as high a degree of heat as is necessary to be applied to the treeing tool itself. I also 70 prefer to affix the handles detachably to the tool, permitting ease in shipment, economy in space, and interchangeability of handles, which advantageous features are rendered possible by my invention. An important 75 feature consists in the angular position, with relation to the handle, or handles, of that portion of the tool which receives the removable electrical heating unit. I find that by this construction of forming the heating 80 socket angularly and, in the case of a treeing iron or similar tool as shown in the drawings, of a separate extension from the work engaging portion of the tool, I secure the advantages of having both the heater 85 and the heat supply wires out of the way of the work. This angular positioning of the heat carrier portion of a heating iron to operate on boots and shoes is a distinct novelty and I wish to claim the same 90 broadly. Also I believe that the provision, in an electrically heated iron to operate on boots and shoes, whereby the heater receiving portion or carrier of the tool is formed or cast thereon as a separate part, distin- 95 guished from boring or recessing a normal portion of the tool, is distinctly novel. In treeing irons, such for example, as that shown herein, this provision of a separate heater carrier is important in enabling the 100 tool to be made light, strong, and of ordinary size for ease and convenience in handling, not weakening it by making a large recess to receive the electrical heater.

Referring to the drawings illustrating a 105 shoe treeing iron,

Figure 1 is a side view of my improved electrically heated hand iron;

Fig. 2 is a bottom plan view;

Fig. 3 is a view partly in cross section on 110 the line 3-3 of Fig. 1.

The treeing iron 1 is formed with its

lower face 2 and edges 3, 4, 5 and 6 of contours appropriate for shoe treeing work, getting into the shank, around the welt crease, across the toe tip, etc. The iron 1 has two upstanding lugs 7 and 8 which are threaded to receive the corresponding threaded portions of the handles. These lugs are preferably cast integrally with the treeing iron 1 and remote from the heated work parts, permitting a preliminary cooling of said lugs. Also cast integrally with the treeing iron 1 is the heater carrier 9, cored to receive the heater 10, which heater has its current supply wires 11 and 12 attached to binding posts carried by a removable plate 13 fitted onto the outer end of lug 9, said binding posts extending through the plate and constituting the plugs 14 and 15 to connect said heater with the detachable conductor 16 to which the supply wires 17 are led from any suitable source of power. The lug 9 not only carries the heater separately from the treeing tool 1, but also holds said heater entirely out of the way of the operation of the iron, and contains the additional feature of holding the current supply wires also out of the way of the iron and the operator. This also enables me to form the handles free of the heat supply wires and to enable a construction permitting air circulation through said handles, not otherwise possible.

While the heating tool just described, without the handles, may, in emergencies be used to apply heat, as also to constitute an immersion water heater, it is desirable, particularly in shoe treeing work, to apply a handle or handles. For many lines of work one handle only is all that is requisite, while in the treeing operation upon most shoes it is desirable to have two handles to enable suitable pressure and manipulation to be applied to the tool by the operator. The treeing iron herein shown may be utilized with either one or both handles. Each handle includes a wooden or non-conducting hand gripping portion 18, bored to receive a metal tubing 19, which tube is provided with a plurality of apertures 20 and is threaded to screw into the correspondingly threaded lugs 7 and 8 on the tool. The ventilated portion having the holes 20 is of suitable length to permit appropriate spacing of the handles 18 from the heated tool 1, insuring air circulation through the tubular part and thus maintaining the handles 18 cool. By having the current supply wires 17 held out of the way and at a distance above the heating tool and the handles I am enabled to form said handles hollow throughout their entire length, if desired, as indicated at 21 in Fig. 1, thus further insuring an air circulation through the ventilated portion of the tubing 19. A rivet or screw 22 through the handles serves to hold each handle in

place on the tubing 19, such provision preferably permitting an adjustment of the handles relatively with said tubing, greater spacing of the handles from the iron lugs 7 and 8 permitting greater insulation. It is convenient to lead the current supply wires 17 entirely out of the way of the operator by guiding same through a swiveled eye bolt 23 on the end of one of the handles. Preferably the tubing 19 may extend beyond the end of the handle 18 and the eye bolt 23 be swiveled therein, the open end of said tubing permitting air circulation already described. The advantages of the electrically heated hand treeing tool above described will be appreciated by those skilled in the art. Each handle being maintained cool and the extreme lightness and simplicity of the entire construction and saving of weight rendering the tool easily manipulated without fatigue. One handle can be detached when desired and the heating unit quickly fitted or removed through the removal of the collar 13 and binding posts thereon. Also the connector 16 and supply wires may be disconnected at any time. The handles can be removed, the tool shipped and the handles and heating unit applied properly, correctly, quickly and without skilled help in shoe factories, repair shops, or the like. In the present application I have elected to claim my invention of an electrically heated tool as applied to a hand instrument, while in my copending application, Ser. No. 62,969, I have elected to claim the invention as applied to a machine.

My invention is further described and defined in the form of claims as follows:

1. An electrically heated treeing iron, comprising a treeing tool, a carrier for an electric heating unit, said carrier constituting a conductor for the heat supply wires out of the way of the treeing tool and a heat insulated handle detachably secured to said tool.

2. An electrically heated treeing iron, comprising a treeing tool, a carrier for an electric heating unit, said carrier constituting a conductor for the heat supply wires out of the way of the treeing tool, projecting lugs on said treeing tool and a pair of detachably secured handles fitted to said lugs, each handle including an air ventilated portion and a non-magnetic portion.

3. An electrically heated treeing iron, comprising a treeing tool, a carrier for an electric heating unit, said carrier constituting a conductor for the heat supply wires out of the way of the treeing tool and a heat insulated handle detachably secured to said tool, in combination with a swiveled guide on the outer end of said handle adapted to coöperate with the heating unit carrier to hold the heat supply wires out of the way of the treeing tool.

4. An electrically heated iron for operat-

ing on boots and shoes, comprising a work-engaging portion and a heater-carrying portion extending from said iron, and a removable heating unit secured to a connector in combination with means on said connector to detachably hold both heating unit and connector on the carrying portion.

In testimony whereof, I have signed my name to this specification, in the presence of two subscribing witnesses.

EDWIN N. CHANDLER.
